UNITED STATES PATENT OFFICE.

ALEXANDER BOGDÁNFFY, OF NEW YORK, N. Y.

MACHINE FOR FILLING AND PACKING MOLDS WITH GRANULAR SUBSTANCES.

1,251,330.

Specification of Letters Patent. Patented Dec. 25, 1917.

Application filed September 28, 1914, Serial No. 863,888. Renewed May 23, 1917. Serial No. 170,563.

To all whom it may concern:

Be it known that I, ALEXANDER BOGDÁNFFY, a subject of the King of Hungary, and a resident of the city of New York, in the county of Kings and State of New York, have invented certain new and useful Improvements in Machines for Filling and Packing Molds with Granular Substances, of which the following is a specification.

10 The present invention relates to improvements in machines for filling and packing molds with granular substances, for instance with treated granulated cork or composition cork.

15 In manufacturing stoppers or sealing disks of the artificial cork type for use in connection with bottle or other closures, it has been the tendency lately to form composition cork rods, which are then cut into 20 stoppers or thin disks. As a mold, a cylinder or tube of considerable length is used, said mold being filled with the granulated treated cork, which is properly packed into the mold and, while in the mold, treated to

25 form a solid rod. The rod so prepared is then removed from the mold, and cut up into pieces of any desired lengths, depending upon the use to which said cut pieces are to be put. In order to obtain a uniform 30 product, it is obviously essential that the molds be packed evenly throughout their lengths. Heretofore there have been proposed several devices for filling and packing molds. In most of these devices, how-

35 ever, the packing rods or plungers are actuated by springs or weights. Inasmuch as the tension of the springs varies as the packing proceeds, obviously an uneven packing of the molds takes place. Where the packing 40 depends upon weights, the distances, from which the weighted packing plungers are dropped, vary as the filling proceeds, producing composite cork rods which are far from being uniform in density throughout

45 their lengths. Again, in some devices the plungers work against weights, that are acting on moving molds. In these devices the momentum of the weighted molds seems to prevent an even packing of the molds.

50 One of the objects of the present invention is to obviate these defects, and to provide a mold filling and packing machine for the purpose specified, which is simple and efficient in operation, and whereby rods are 55 produced which are substantially even and uniform throughout the lengths thereof.

Another object of the invention is to provide a simple feeding mechanism which will insure a positive and uniform feeding to the molds and which automatically stops 60 the feeding as soon as the molds are completely filled.

With these and other objects in view, which will more fully appear as the nature of the invention is better understood, the 65 same consists in the combination, arrangement and construction of parts hereinafter fully described, pointed out in the appended claims and illustrated in the accompanying drawings, it being understood that many 70 changes may be made in the size and proportion of the several parts and details of construction within the scope of the appended claims without departing from the spirit or sacrificing any of the advantages of the 75 invention.

One of the many possible embodiments of the invention is illustrated in the accompanying drawings, in which:—

Figure 1 is a vertical section taken 80 through a machine constructed in accordance with the present invention; Fig. 2 is a front elevation thereof, partly in section; Fig. 3 is a plan view of the same; Fig. 4 is a portion of a section taken on line 4—4 of Fig. 85 1; Fig. 5 is a portion of a section taken on line 5—5 of Fig. 1; Fig. 6 is a portion of a section taken on line 6—6 of Fig. 1; Fig. 7 is a section taken on line 7—7 of Fig. 6 on an enlarged scale; Fig. 8 is a portion of 90 a section taken on line 8—8 of Fig. 1; Fig. 9 is a vertical section taken through a portion of the cross head of the machine; Fig. 10 is a section taken on line 10—10 of Fig. 9; Fig. 11 is a front elevation of the detail 95 shown in Fig. 9; Fig. 12 is a side elevation of a detail of the feeding means actuating mechanism; Fig. 13 is a front elevation of the detail shown in Fig. 12; Fig. 14 is a section taken on line 14—14 of Fig. 12; Fig. 15 is a vertical section taken through 100 another detail of the feeding means actuating device; Fig. 16 is a section taken on line 16—16 of Fig. 15; Fig. 17 is an elevation, partly in section, of a detail of the packing or tamping plunger; Fig. 18 is a plan view on an enlarged scale of the detail 105 of the device shown in Fig. 10; Fig. 19 is a section taken on line 19—19 of Fig. 18; Fig. 20 is a section taken on line 20—20 of Fig. 19; Fig. 21 is a section taken through 110 a further detail of the invention; Fig. 22

is a front elevation of the detail shown in Fig. 21; Fig. 23 is a vertical section taken through one of the valves controlling the supply of granular material to the molds; Fig. 24 is a plan view of said valve; and Fig. 25 is a perspective view of the trough or hopper holding the granular material in its loose state.

In the drawings, the numeral 30 indicates the frame of the machine, including side sections 31, which are united by front and rear plates 32 and 33. In the lower portion of the frame is journaled a horizontally arranged shaft 34, to which are fixedly attached two disks 35 and 36, the latter one serving as a pulley, by the intermediary of which the shaft is driven. The disks 35 and 36 are provided with wrist-pins 37, which are engaged in the usual manner by pitmen 38, that are connected with a cross head 39, the latter being reciprocably mounted in vertically extending guides 40, which are formed upon the inner faces of the side sections 31 of the frame. In the cross head 39 is provided a plurality of vertically disposed cylindrical bores 41, in the case illustrated, for instance, twelve, the machine illustrated being built for filling and packing simultaneously twelve molds. It is, however, obvious that any other number may be provided according to the requirements without departing from the spirit of the invention. Each bore is closed at its lower end by a cover 42, having a centrally arranged opening 43 relative to the bore. Through each of these openings projects a packing or tamping plunger 44, to which is attached a weight 45, that is reciprocably disposed within the corresponding bore 41. The tamping plungers are provided at their lower ends with cylindrical heads 46, that fit the molds hereinafter to be described. The plungers extend into vertical tubular guides 47, the latter being carried by a trough-shaped hopper 48, that extends from side to side of the main frame of the machine, and is attached to said sides, for instance, by rivets. The tubular guides extend through the bottom of the hopper and register with apertures 49 in a mold-support 50. This mold-support comprises a frame that is substantially I-shaped in cross section and extends from side to side of the main frame of the machine, and is attached to said sides in any suitable manner. The apertures 49 are formed in the horizontal head portion 51 of the mold-support, and in alignment with these apertures are formed in the horizontal foot portion 52 of said mold-support recesses 53, the front ends of which are adapted to be closed by springs 54, the latter being fastened to the foot portion 52 of the mold-support. In the underface of the head portion 51 of the mold-support the apertures 49 merge into conical recesses 55,

into which and into the recesses 53 are adapted to be inserted the conical heads 56 of tubular molds 57. The lower ends of the molds are before insertion closed by covers, their upper ends being left open to receive the granular material with which they are to be filled and packed. In inserting the molds, first their upper ends are seated into the recesses 55 in the head of the support, their lower ends being then brought into the recesses 53 in the foot of the mold support, the springs 54 having been previously depressed, to be restored to their normal positions as soon as the molds are properly in place. The springs obviously keep the molds in place during the filling and packing operations.

The means for feeding the granular material from the hopper through the apertures 49 into the molds comprises a plurality of slide valves 58, one for each mold. These valves are disposed in guides 59 between the bottom of the hopper and the horizontal head portion 51 of the mold support. Each valve is provided with two ports 60 in line with a set of two openings 61 in the bottom of the hopper, that opening in the bottom of the hopper through which the corresponding tubular guide 47 leads being located between and in the line of the openings 61, so that, as the slide valve is being reciprocated and moved to one side, for instance into the position shown in Fig. 1 of the drawings, one of the valve ports registers with the aperture 49 in the mold-support and the other valve port with one of the set of openings 61 in the bottom of the hopper and, when moved to the other side, one of the ports registers again with the aperture 49 and the other one with the other one of the set of openings 61. With each valve is associated an actuating mechanism. These actuating mechanisms are independent of each other, and comprise each a two-armed lever 62, that is fulcrumed at 63 to a bar 64, that is carried by the front and rear plates 32 and 33 of the frame. To the ends of this lever are pivoted at 65 downwardly extending links 66, to each of which is pivoted at 67 a bellcrank lever 68. These bellcrank levers are fulcrumed at 69, 69 to the trough or other stationary part of the machine, in their slotted ends 70 being seated pins 71, that are attached to the corresponding slide valve 58. Each of the links 66 carries near its upper end a spring pressed lug 72, for instance in the form of a pin 73, that is slidably disposed in a housing 74, the latter being fixedly attached to the link. A spring 75 serves to project the pin 73 through an opening in the housing 74. With each set of lugs 72 co-operates a slide 76, which is arranged in a horizontally extending guide 77 in the top of the cross head 39. These slides are located parallel to each

other and are provided within the bores 41 in the cross head with grooves 78, in which teeth 79, that are formed upon the weights 45, are adapted to be seated in a manner 5 hereinafter to be described. To each of the links 66 is pivoted at 80 a cam 81, that is projected toward the cross head by a spring 82, a stop 83 determining the outermost position of the cam. These cams serve to actuate, as will hereinafter appear, the slides 76, which, in turn, act upon the lugs 72.

The connections between the cross head of the machine and the packing plungers are made as follows: Each of the plungers is 15 provided with ratchet teeth 84 down from the weight 45 to a distance which is somewhat greater than the height of the cross head. To each cover 42 are pivoted at 85 jaws 86, that surround the plunger, and are 20 provided with beveled faces 87, coöperating with the correspondingly shaped ratchet teeth 84. A spring 88, engaging the jaws, tends to keep them in engagement with their plunger. For the purpose of disengaging, 25 at times hereinafter specified, a set of jaws from its plunger, there is shiftably mounted in a guide 89, associated with each cover 42, a plate 90, that has a trapeziform opening 91, into which extensions of the jaws project. The width of the opening 91 decreases 30 gradually downward, as clearly shown in Fig. 11 of the drawings, the extensions of the jaws being normally seated in the widest portion of the opening 91 (Fig. 11). When, 35 therefore, the plate 90 is shifted upward, obviously, it will cause the jaws to open against the action of the spring 88. For the purpose of actuating the plates 90, there are shiftably mounted upon a rail 92 blocks 40 92', which are adapted to be projected independently of each other into the paths of the plates 90 by bellcrank levers 93, in engagement with said blocks, or by any other suitable means. A rail 94 is attached to the 45 front plate 32 of the frame, and is adapted to engage, when the cross head reaches in its travel its uppermost point, those plates 90 which have been previously shifted to their upper positions by blocks 92'.

50 The operation of this machine is as follows: Before starting the operation of the machine, the cross head, with the plungers carried thereby, is brought into its uppermost position (Fig. 1). Empty molds are 55 then placed upon the support 50, the material to be packed therein being poured into the hopper 48. This hopper, having slanting walls and partitions 95, that are also slanting, will cause the material therein to 60 flow continuously toward the openings 61 in the bottom thereof, and through the latter into those valve ports 60 which happen to be in registering positions with one or the other one of said sets of openings. To understand the operation of the machine, it is

necessary to describe the filling and packing of one mold only. Let us suppose that the single mold shown in Fig. 1 of the drawings is to be filled and packed, and that the plunger coöperating therewith is clutched to the cross 70 head by the coöperating ratchet teeth and jaws above described. There being no charge in the mold, the descending plunger does not change its position relative to the cross head, but will upon the next upward stroke occupy 75 again the position shown in Fig. 1 of the drawings. It should be noted that that end of the slide 76, which is nearer the front plate 32, projects beyond its guide 77. At the first downward stroke, the projecting 80 end of the slide comes into contact with its corresponding cam 81, which shifts the said slide so that its other end will project beyond the guide 77. At the next upward stroke, the projecting end of the slide comes into 85 contact with that lug 72 which is nearer the rear plate 33, thereby shifting, by the intermediary of the links 66 and bellcrank levers 68, the slide valve 58. In the position shown in Fig. 1 of the drawings, obviously 90 that port 60 which is in alinement with one of the openings 61 in the bottom of the hopper is filled with granular material, and, as the valve is shifted in the direction of the arrow shown in Fig. 1 of the drawings, the 95 said port will register with the aperture 49, so that the granular material therein is fed into the mold 57. The port 60 which registers in the position shown in Fig. 1 of the drawings with the mold, is thus brought into 100 alinement with the other one of the set of openings 61, to receive its charge. Upon the next downward stroke, first the slide 76 is shifted to the other side, and the plunger packs the charge into the mold to a density 105 which depends wholly upon the weight of the plunger and weight 45. The plunger is caused to ascend during the packing operation a distance equal to the height of the compressed charge, the jaws in coöperation 110 with the ratchet teeth holding it in such position during the next upward stroke. The cycle of operation now described is then repeated, that is to say as the plunger ascends again, the same quantity of material 115 is fed into the mold on top of the already packed material, and upon the downward stroke the charge is compressed to the density of the previously compressed charge and into integrity therewith. These operations are repeated until the plunger reaches 120 its uppermost point in relation to the cross head, at which position the teeth 79 engage the grooves 78 in the slide 76, thereby preventing a shifting of the slide 76 by the cams 125 81, whereby the feeding will automatically stop. The filled and packed mold is then removed from the support, closed by a cover, and is thus ready for further treatment. A new mold is then placed upon the 130

support and the corresponding block 92' shifted in the path of the plate 90 associated therewith, which will result, upon the next downward motion of the cross head, in 5 a disengagement of the pawls from the ratchet teeth of the plunger, which will thus drop to its lowermost position. An air port 96 near the bottom of the corresponding cylindrical bore permits the air below the 10 weight to escape, yet it causes the formation of an air cushion which will deaden the blow of the falling weight 45. At the next upward stroke, the plate 90 is shifted by the transverse rail 94 to its normal position 15 (Figs. 1 and 11), whereby the spring 88 engages the jaws with the ratchet teeth of the plunger, after which the block 92' is brought back manually to its inoperative position, the filling of the new mold then commences 20 and proceeds in the manner above described. The lugs 72 are resiliently fastened to the links, to prevent shocks and jars.

From the foregoing it appears that each plunger is positively connected to the cross 25 head during its entire upward stroke, the jaws 86 upon the cover 42 of the cross head being in engagement with the ratchet teeth 84 on the plunger. As there is no mechanism provided which would disengage the 30 jaws from the plunger, it is obvious that the plunger will be positively connected with the cross head at the downward stroke. However, near to the end of the downward stroke the plunger comes into contact with 35 the loose material in the mold, and is thereby temporarily disconnected from the cross head, that is to say the plunger slides up one or more teeth in relation to the cover 42 of the cross head, this distance corresponding 40 to the height of the last charge that is being compressed. It is obvious, therefore, that the plunger is released from the cross head during the act of compression. The compression being finished, the 45 cross head starts on its upward stroke carrying with it the plunger, the jaws in coöperation with the ratchet teeth again positively connecting the plunger with the cross head. The cycle now described is repeated 50 during each turn of the main shaft of the machine until, as above described, the plunger reaches its uppermost point in relation to the cross head.

It should be observed that measured 55 quantities of material are fed into a mold at a time, and each charge is compressed or packed individually. Inasmuch as the degree of compression depends entirely upon the weight, the plunger being released from 60 the cross head during the act of compression, the rod will be even and uniform throughout the length thereof. The plunger drops, as it were, always from the same height by reason of its being released from 65 the cross head in relation to the previously

compressed charges always at the same point. The machine differs essentially from those heretofore in use, which rely either upon springs, the tensions of which vary at each stroke of the plunger, or they rely 70 upon weighted plungers which are dropped from varying heights as the filling and packing proceeds. It differs also from those in which weight controlled moving molds are used. All of these machines produce 75 uneven packing.

The density of the rod in the present machine is predetermined by the weight of the plunger and weight 45 and may be varied, at will, by increasing or decreasing such 80 weight.

What I claim is:—

1. In a machine for filling and packing molds with granulated material, the combination with a support for the mold, of a 85 weighted plunger in operative relation thereto, a cross head, a connection between said plunger and cross head, whereby said plunger is positively connected with said cross head during the entire upward stroke 90 and part of its downward stroke but is allowed to act by its weight near the end of its downward stroke, feeding means associated with said mold-support, means actuated by said cross-head for operating said 95 feeding means, and means carried by said plunger for rendering said first named means inoperative when the filling of the mold has been completed.

2. In a machine for filling and packing 100 molds with granulated material, the combination with a stationary mold, of means for intermittently feeding measured quantities of loose material thereto for forming a single article, of a cross head, a weighted 105 plunger shiftably arranged upon said cross head in operative relation to said mold, and a connection between said plunger and said cross-head, whereby said plunger is positively connected with said cross-head during 110 the entire upward stroke and part of its downward stroke, but is allowed to act by its weight upon each individual charge from a distance which is always the same with relation to the previously compressed 115 charges.

3. In a machine for filling and packing 120 molds with granulated material, the combination with a stationary mold, of means for intermittently feeding measured quantities of loose material thereto for forming a single article, of a cross head, a weighted 125 plunger shiftably arranged upon said cross head in operative relation to said mold, a connection between said plunger and said cross-head, whereby said plunger is positively connected with said cross-head during 130 the entire upward stroke and part of its downward stroke, but is allowed to act by its weight upon each individual charge 130

from a distance which is always the same with relation to the previously compressed charges, means actuated by said cross head for operating said feeding means, and means 5 carried by said plunger for rendering said feeding means operating means inoperative when the filling of the mold has been completed.

4. In a machine for filling and packing 10 molds with granulated material, the combination with a stationary mold, of means for intermittently feeding measured quantities of loose material thereto for forming a single article, of a cross head, a weighted plunger shiftably arranged upon said cross head in operative relation to said mold, and a connection between said plunger and said cross-head, whereby said plunger is positively connected with said cross-head during 15 the entire upward stroke and part of its downward stroke, but is allowed to act by its weight upon each individual charge from a distance which is always the same with relation to the previously compressed charges, 20 whereby said plunger is raised in relation to said cross head at each downward stroke the same distance.

5. In a machine for filling and packing 25 molds with granulated material, the combination with a stationary mold, of means for intermittently feeding measured quantities of loose material thereto for forming a single article, of a cross head, a weighted plunger shiftably arranged upon said cross 30 head in operative relation to said mold, a connection between said plunger and said cross head, whereby said plunger is positively connected with said cross head during the entire upward stroke and part of 35 its downward stroke, but is allowed to act by its weight upon each individual charge from a distance which is always the same with relation to the previously compressed charges, whereby said plunger is raised in 40 relation to said cross head at each downward stroke the same distance, means actuated by said cross head for operating said feeding means, said plunger rendering said feeding means operating means inoperative when it 45 is raised to its highest point after the filling of the mold has been completed.

6. In a machine for filling and packing 50 molds with granulated material, the combination with a support for the mold having an aperture through which the material is fed into the mold, of a hopper provided with two openings in line with said aperture, a slide valve between said hopper and said mold-support having two ports adapted 55 to register alternately with said aperture and one of said openings, a cross head, a

weighted plunger shiftably arranged upon said cross head in operative relation to said aperture, a connection between said plunger and said cross head, whereby said plunger is positively connected with said cross head during the entire upward stroke and part of its downward stroke, but is allowed to act by its weight near the end of its downward stroke, links connected with said 65 slide valve, and means carried by said cross head for actuating said links, whereby said slide valve is reciprocated.

7. In a machine for filling and packing 70 molds with granulated material, the combination with a support for the mold having an aperture through which the material is fed into the mold, of a hopper provided with two openings in line with said aperture, a slide valve between said hopper and said 75 mold-support having two ports adapted to register alternately with said aperture and one of said openings, a cross head, a weighted plunger shiftably arranged upon said cross head in operative relation to said aperture, a connection between said plunger and said cross head, whereby said plunger is positively connected with said cross head during the entire upward stroke and part of its downward stroke, but is allowed to act by its weight near the end of its downward stroke, links connected with said slide valve, and means carried by said cross head for actuating said links, whereby said slide valve is reciprocated, said last named means being 80 set to operative positions, in turn, by said links.

8. In a machine for filling and packing 85 molds with granulated material, the combination with a support for the mold, of a cross head, a weighted plunger having ratchet teeth shiftably arranged upon said cross head in operative relation to said mold-support, spring pressed jaws carried by said cross head coöperating with said 90 ratchet teeth, whereby said plunger is positively connected with said cross head during the entire upward stroke and part of its downward stroke, but is allowed to act by its weight near the end of its downward stroke, means carried by said cross head for disengaging, at will, said jaws from said 95 plungers, and means in the path of said last mentioned means for rendering the same inoperative.

Signed at New York, in the county of New York, and State of New York, this 110 18th day of Sept., A. D. 1914.

ALEXANDER BOGDÁNEFFY.
